UNITED STATES PATENT OFFICE

JOSEPH DIGRIUS, OF BROOKLYN, NEW YORK

STACK WATER HEATER AND STORAGE DEVICE

Application filed February 21, 1930. Serial No. 430,162.

My invention relates to an improvement in a stack water heater and storage device and its novelty consists in the adaptation and arrangement of parts as will be more fully hereinafter pointed out.

A large amount of heat passes off from a furnace through the flue or stack pipe which is absolutely lost as it goes up the chimney.

Many devices have been invented to try and utilize this tremendous amount of lost energy but none of them furnish a means of heating a house supply of hot water and maintaining the same hot.

My device does not only heat a full house supply of hot water by means of stack waste heat but maintains the water in storage at a temperature by means of stack waste heat ready for instant use.

Referring to the drawings Figure 1 is a longitudinal section of my device on the line 1—1 of Figure 2.

Figure 2 is a front end view of my device looking in at Figure 1 from the right hand end and with a portion broken away in order to show the interior construction.

Figure 3 is a longitudinal section of another embodiment of my device on the line 3—3 of Figure 4 and

Figure 4 is a vertical cross section on the line 4—4 of Figure 3 and with a portion broken away to show the interior construction.

In the drawings 5 is a drum of cylindrical shape having a cap 6 fitting over the front end and being removable therefrom. An incoming pipe 7 running from the stack pipe (not shown) of a furnace passes through said cap 6 into the drum 5 and a second pipe 8 passes from said drum 5 through said cap 6 and back into the said stack pipe at a point nearer the chimney than pipe 7.

A central plate 9 is rigidly mounted longitudinally in the drum 5 at 10 so that it runs from the front end of the same to a point near the rear end.

A hot water storage tank 11 is rigidly mounted at about the center of the drum 5 by means of brackets 12.

A cold water supply pipe 13 having the usual control valve 14 is run into the drum 5

at 15 and is run longitudinally of the drum 5 all the way around the cylindrical surface of the hot water storage tank 11 forming longitudinal loops 16 around the same. The inner end of said pipe 13 enters the bottom of the tank 11 at 17.

A hot water pipe 18 runs from the upper side of the tank 11 and connects directly to the house hot water supply system (not shown).

The drum 5 has a clean out sliding door 19 of usual construction mounted at the back end and bottom clean out doors 20 and 21 of usual construction mounted at the sides of the bottom of said drum 5.

In operating my device the hot gases from the stack will enter pipe 7 and pass through the same into the drum 5 and because of the dividing central plate 9 will pass back of the rear end of same and be drawn into the outgoing pipe 8 back into the stack pipe. The cold water coming into the pipe 13 and passing around through the loops 16 will be thoroughly heated by said hot gases and as this heated water passes into the tank 11 it will be maintained hot because of the continuous flow of hot gases through the passages of the drum 5 and constantly around all sides of the tank 11.

Whenever hot water is drawn off through the house hot water system from tank 11 new cold water flows in through pipe 13 and will in turn be heated and stored in the same manner as previously described.

Another form of my device is shown in Figures 3 and 4 in which the construction and operation are the same as already described except as to tank 11 which has a cold water inlet compartment 11a and a hot water storage compartment 11b separated by the partition 11c. The cold water supply pipe 13 discharges directly into said compartment 11a and the water flows from the compartment 11a to 11b through a series of pipes or loops 16a in which the water is thoroughly heated and then stored in compartment 11b to be drawn off as desired and as previously described.

I claim:

1. In a stack water heater the combination

- of a drum divided by a central plate running almost to the rear end, an inlet and an outlet connection to the stack pipe at the front end of said drum, a water tank mounted in the center of said drum, a cold water feed pipe running into said drum and longitudinally around said tank and entering the same at one point and an outgoing hot water pipe running from said tank at a different point.
- 5 2. In a stack water heater the combination of a drum, means for insuring a circulation of stack gases therethrough comprising an inlet and an outlet adapted to be connected to a stack pipe, one on either side of a dividing plate mounted in said drum extending the entire length of the drum except at the rear end, means for circulating water therein consisting of a cold water supply pipe forming a coil running longitudinally of said drum and around a tank rigidly mounted in said drum said pipe entering said tank at one point and an outgoing hot water supply pipe leaving said tank at a different point from said incoming pipe.
- 10 3. In a stack water heater the combination of a drum divided by a central plate running almost to the rear end, an inlet and an outlet adapted to be connected to a stack pipe at the front end of said drum, a water tank mounted in the center of said drum, a cold water feed pipe running into said drum and longitudinally around said tank and entering the same at one point and an outgoing hot water pipe running from said tank at a different point and a clean out means in the end and bottom of said drum.
- 15 4. In a stack water heater the combination of a drum adapted to be connected to a stack pipe, means for insuring a circulation of stack gases therethrough, means for circulating cold water therein for heating the water, means for storing said heated water therein and clean out means in the end and bottom of said drum.
- 20 5. In a stack water heater the combination of a drum adapted to be connected to a stack pipe in a manner to insure the circulation of stack gases therethrough, means therein for circulating cold water to be heated, means for storing said heated water within said tank and within said cold water circulating means, means connecting said hot water storage means to a hot water circulation pipe and a clean out means in the end and bottom of said drum.
